DESIGN FOR A SHOE

Milan G. Cheyovich, Detroit, Mich.

Application June 20, 1936, Serial No. 63,410

Term of patent 3½ years

To all whom it may concern:

Be it known that I, Milan G. Cheyovich, a citizen of the United States, residing at Detroit, county of Wayne, in the State of Michigan, have invented a new, original, and ornamental Design for a Shoe, of which the following is a specification, reference being made to the accompanying drawing, forming part thereof.

Fig. 1 is a top plan view of a shoe showing my new design.

Fig. 2 is a side elevation of my shoe.

I claim:

The ornamental design for a shoe, as shown.

MILAN G. CHEYOVICH.
